MOLD CONSTRUCTION FOR LINE CASTING MACHINES

Clarence E. Brandon, Jr., St. Louis, Mo.

Application March 4, 1939, Serial No. 259,777

15 Claims. (Cl. 199—47)

This invention relates to improvements in mold construction for line casting machines, and more particularly to an improved mold structure embodying adjustment features for variation, over 5 a wide range, of the point size of type to be cast, and further including features whereby the mold head assembly may be used, selectively, as an attachment, adjunctively to the metal pot of line casting machines for the purpose of casting 10 large display type above the sizes ordinarily possible in the use of standard line casting machines.

Among the more important objects of the invention is an improved provision of a mold structure for line casting machines, in which the liner elements are at all times secured to and form parts of the mold, whereby to obviate the necessity of removing and replacing conventional types of liners when changing from slugs of one point size to slugs of a different point size. Various provisions have heretofore been made in the art for adjusting one or more of the elements forming the mold cavity, in an attempt to obviate removal of the mold from the mold disc 20 incident to a change in point size, and further in an attempt to reduce the considerable and expensive stock of liners now prevalently required to care for the wide range of different point sizes of type to be cast by the machine. None of 25 these efforts has, as far as is known, been successful to a degree to warrant general adoption. Accordingly, in prevalent practice it is necessary to remove the cap from the base of the mold, reinsert a pair of liners of the selected size, then to reassemble the cap and base of the mold. It 30 is accordingly a further, general object of the invention to obviate many of these operations incident to a change in point size of type in the slug to be cast.

40 A further important object of the invention is attained in a marked reduction of the stock of liners heretofore required due to changes in point size. The changes in point size for the slugs existing within a range, for example, between five point to fourteen point inclusive, including a usual five and one-half point size, require the operator to keep at hand some twenty-two liners to cover these different point sizes within the range noted, there being two liners heretofore 45 required for each given point size of slug to be cast. It is needless to point out that the expense of this considerable stock of liners entails an investment desirable to be minimized.

Yet another object of the invention is attained 50 in improved adjustment features for a movable

wall element of the mold cap, for example, which is provided with a single adjustment agency so designed that the movable wall element when adjusted incident to a change in point size, is automatically levelled in a manner to assure the 5 same depth of the mold cavity from end to end thereof.

A still further object of the invention is attained in a casting attachment adapted for use with a type metal pot, and heating means therefor to enable the machine operator or printer to set up and cast, as required, particularly the larger display types, for example, from thirty-six point to one hundred and forty-four point, it being noted that this attachment is particularly 10 desirable for use in connection with the metal pot of existing types of line casting machines and is designed to employ matrices of known form as the type-defining elements of the attachment.

20 Yet another object of the invention is attained in an improved adjustable recessed sliding mold of general adaptation for use in or with line casting machines, the assembly of which mold is extremely simple in construction, and such that it 25 may be attached, either in the mold disc of standard machines without any alteration being necessary, or may be used adjunctively, as the attachment referred to in the object next above stated.

The foregoing and many other objects of the 30 invention will appear from the following detailed description of certain presently preferred embodiments of the invention, particularly when considered in connection with the accompanying drawings forming a part hereof, and in which:

35 Fig. 1 is an elevation in perspective of an improved mold assembly constructed in accordance with the invention, and in a form adapted for use as an attachment to a metal pot of a line casting machine; Fig. 2 is a vertical section through the mold head structure of the arrangement of Fig. 1; Fig. 3 is a horizontal section of the mold head structure of Figs. 1 and 2, as viewed along line 3—3 of Fig. 2; Fig. 4 is a front elevation of the mold head structure of Figs. 1 and 2 with the 40 type or matrix tray in open position, Fig. 4 showing one end portion in section, and Fig. 5 is a front elevational view of the mold assembly as same would appear when mounted in a conventional type of mold disc of a line casting machine.

45 Referring now by characters of reference to the drawings, the mold proper includes a base 10 and a cap portion generally indicated at 11, the base and cap constituting the halves of the mold. 50

55

The mold as shown, is of so-called recessed type the general construction and usage of which, but for present improvements, are well known to those skilled in the art and require no amplified description. The usual mounting of the mold assembly is substantially as shown by Fig. 5 where-in the numeral 12 indicates the body of a mold disc usually provided with a plurality of cavities 13 for the reception of the mold, and the mold 10 being retained in the disc through a plurality, shown as a pair, of screws 14. The screws 14 project depthwise from the periphery of the mold disc, and bear against the cap of the mold whereby the latter is held firmly in clamped relation in the disc. The periphery of the disc is shown as provided with the usual gear teeth or the like 16.

The cap 11 of the mold is provided with a plurality of recesses extending rearwardly from or depthwise of the open front face of the mold structure, these recesses being indicated at 17, and as appears, are defined by and located between a plurality of partition elements 20. Opening into each or a plurality of the recesses 17, are metal conducting passages or conduits 21 which are supplied with the molten metal at the time of casting, through agencies hereinafter more fully explained.

In order to provide for a variation of the width or depth of the mold cavity, i. e., an expansion or contraction of the cavity to care for different point size of the type to be cast, the present improvements include a movable longitudinal wall element defining what may be considered either the top or one of the longitudinal walls of such cavity. This movable element which, for present convenience, is designated as an elevator, in indicated generally at 22, and extends from end to end of the cavity-forming portion of the mold. The elevator 22 is provided with a shouldered recess 23 best shown by Fig. 2, and due to this rabbed construction of the forward upper face of the elevator, there results a shoulder 24 on its lower portion which coacts with the lugs of the matrices to establish their position for casting under certain conditions as will appear from the drawings and later description. Projecting rearwardly from the forward bar or body portion of the elevator 22, are a plurality of spaced partition elements 25 best appearing in Fig. 3; these partition elements are of a width to provide a working clearance thereof, in the recesses 17 of the cap, being fitted thereto in such manner that the tongues 25 will substantially prevent any escape of the casting metal above and outwardly of the tongues, and the working fit being further such that no appreciable frictional resistance between the tongues 25 and partitions 17 impairs the adjusting movement of the elevator 22 as hereinafter described. It will be noted that the tongues 25 project inwardly of the mold, so as to engage the rear wall 26 of the mold cavity in the cap.

It is a preference to provide for vertical adjustment of the wall element or elevator 22, through a single substantially centrally located adjusting agency exemplified in the drawings by the screw 30, a threaded seat 31 being provided therefor in that portion of the cap just above the mold cavity. The lower end of screw 30 terminates in a flared swivel end 32 occupying a correspondingly shaped recess therefor in the upper portion of the elevator 22. This recess is preferably slotted in form (not shown) so as to facilitate the assembly of the screw to the elevator. Above the mold recess or cavity is provided an

adjusting recess 33 into which projects the head portion 34 of the screw 30, which head may be either of square or hexagonal shape, or of other form suitable for actuation by a wrench or like tool. A lock nut 35 is provided so that once the elevator is adjusted to the desired height according to the point size of the type to be cast, a wrench (not shown) may be inserted into opening 33 for engagement not only with the head 34 of the screw, but may further be used to actuate the lock nut 35.

In order to provide a firm abutment for the ends of the elevator and hence to be assured of the point size of type to be cast, as well as of the uniformity of the width of the resulting mold cavity in the cap, there is provided at or near each end of the elevator 22, but within the confines of the mold parts, a stack of liners 40. These liners may each be of uniform thickness, say of two points, or if desired, may be of a variety of thicknesses, but each thereof is preferably apertured substantially between its ends as at 41, for the reception of a headed pivot pin 42 which, for convenience, may be threaded into securing with the base 10 of the mold. It results from this arrangement that the liners 40 of each stack may be selectively swung about their pivot say through an angle of 180 degrees, from an out-of-action position shown by the major part of the stack in Fig. 4, to an in-action or functional position beneath the elevator 22 as shown by the lesser group in Fig. 4. However, due to the location of the pivot openings and pin 42 of each stack, between the ends of the associated liners, it will appear that all of the liners 35 of the given group remain in superposed or stacked relation irrespective of the number thereof which are swung from out-of-action, to in-action position.

For the purpose of providing a combined retainer for the liners which are out of use, and a gauge element to inform the operator definitely of the adjusted elevator height, there is provided at each end of the elevator a T-shaped resilient element 43 secured as by pins or the like 44, to the end of the body of the elevator. The retainer and gauge elements 43 thus move upwardly or downwardly with the elevator, but may be manually deflected to enable withdrawal or reinsertion of the liners as may be required.

Referring further to the base 10 of the mold, it is a preference to form the forward face 45 thereof, with three grooves 46 and intervening rail portions 47. The three grooves and intervening rails are preferably employed to provide a wider range of adjustment in heights of the matrices such as 50, as will best appear from the section in Fig. 2, it being understood that the grooves may be selectively or collectively utilized for the reception of the lugs of the matrices going to make up the assembled line.

There is shown as a means for securing together the cap and base of the mold, an expedient found in the present disclosure in a hinge bolt 51 interfitting the slot 52 and provided with a nut 53, all as appearing at the left hand side of Fig. 4, the hinged bolt being carried by a pivot 55 which may be carried by the mold base.

When the mold is employed in the standard line casting machines, the manner of setting up the matrices for the purpose of casting the slug is or may be identical with the procedure and order of events now followed in connection with such machines, and hence need not be described in detail. Assuming, however, that the mold is

prepared for casting and it is desired to change from one point size of type to another, with the front of the mold open, as appears in Fig. 4, the wrench is applied to the head 34 of screw 30 after loosening the set screw 35, and through manipulation of the screw 30 the elevator 22 is brought to the desired height above base 10, as will be indicated by the number of liners cleared by the lower edges of the retainer and gauge elements 43. Usually the elevator will be brought slightly above this position so as to provide for certain clearance in inserting the predetermined number of the liner elements 40 beneath the ends of the elevator. This is obviously done by swinging the liner elements which are now freed by the retainer, into operative or functional position under the elevator ends. Following this, the adjusting screw 30 is threaded down to bring the elevator firmly against the stacked spacers thereunder, the lock nut 35 is threaded up tightly, and the mold is ready for casting a slug of predetermined point size.

Referring now more particularly to the attachment shown by Figs. 1 and 2, the mold proper thereof is or may be identical with that shown by Figs. 3 and 4, including the base portion 10 and cap 11. Accordingly, the description of the elements for defining the mold cavity, as well as that applicable to the elevator, spacers, liners and adjustment features, will apply equally to the mold elements proper, as shown by Figs. 1 and 2.

According to preference, the attachment is detachably carried by the metal pot of the machine with which it is utilized, but may obviously be applied to an entirely separate melting crucible or other structure. A portion of the pot wall is indicated at 60, to which the attachment is held as by clamp structure 61 which may be of any suitable, preferably simple construction. The clamp 61 supportingly engages a reversely curved metal conduit which may be described as a gooseneck conduit indicated generally at 62. The lowermost portion of conduit 62 is considerably enlarged, and is upturned from the portion adjacent the bottom of the pot so as to form a cylinder 63 open at its upper or outer end for the reception of a plunger or piston 64. The piston 64 is provided with an upwardly extending actuation rod or handle 65, which is broken away for clearness of illustration of other parts, but which extends above the bath of metal in the pot a distance to be safe for manual engagement by the operator.

The vertical or riser portion of the gooseneck tube 62 merges into a flared or widened throat structure indicated generally at 66. This is preferably so formed as to tend to prevent even any minor localized freezing effect of the metal prior to the time it reaches the mold cavity, and for this purpose the portion 66 is shown as enclosed by an insulating material 67 in which is embedded a number of turns of resistance wire 70 supplied from any suitable source of electrical energy (not shown).

As a convenient means of attachment of the conduit to the mold head structure comprising the mold and immediate appurtenant parts, an outer end element 71 forms a continuation of the conduit 62, particularly the part 66 thereof, and is mitered as shown at 72 so as to engage a corresponding internally mitered portion 73 in the mouthpiece element 74, which in the present instance constitutes a backing or support for the remaining parts of the mold head. By closely

machining the mitered end surfaces of the fitting 71, and the seat therefor in element 74, there is provided a metal-tight connection which may be easily broken for disassembly of the mouthpiece and conduit, by endwise sliding movement of the element 74. It will be noted that the channels 21 entering the mold cavity, are projected rearwardly and horizontally through the element 74 for communication with the conduit portion 66.

It is a preference to provide for displaceable securement of the mold proper, specifically the base 10 thereof, to the element 74, as by hinging together their lower horizontal margins through the hinge structure 75. When the front of the mold is open, it is at times desirable to maintain the mold in adjacency to the mouthpiece 74, and for this purpose there are provided at the ends of elements 10 and 74, suitable securement means exemplified by a pair of latches 76, each pivoted to the mold base 10 and engaging a companion pin element 77 on the mouthpiece. One such latch assembly is preferably provided on each of the opposite ends of the mold head, enabling the parts to be retained in temporary assembly in the relation shown by Fig. 1.

Hingedly connected to the lowermost horizontal portion of the mold base 10 of the attachment, is a displaceably mounted type tray or matrix tray generally indicated at 80, provided with a hinge structure 81 which serves pivotally to relate the parts 80 and 10. This matrix-receiving element 80 is essentially in the form of an open top and open side rectangular structure including a fixed end closure element 82, and a second adjustable such element 83, together with a front or matrix-backing wall portion 84. This front wall portion of the type tray is shown as provided along its inner face with three rails 85, the upper of which is somewhat wider than the two lower rails, and which result in intervening groove portions 86. These rails and grooves correspond in position and relation to the rails 47 and intervening groove portions 46, as best appears from Fig. 2, the rails and grooves coacting with the relatively recessed and projecting lateral portions or lugs of the matrices for positioning them, as will be readily understood by those skilled in the art.

To provide for adjustment of the movable end wall or abutment 83 of the type tray, according to the pica length of slug to be cast, the element 83 is secured to an adjusting rod 90 which extends to the left of the type tray for manual actuation, although not shown in its full preferred length. When the type stick is set up and disposed in the tray 80, the movable abutment 83 is moved through actuation of the rod 90, so as to compact the line of type in the tray, and thereupon is tightened up a wing nut 91 (Figs. 1 and 3), this screw abutting the adjusting rod 90 so as firmly to clamp the movable wall 83 in the desired position.

For the purpose of positively locking the type tray, the mold and the backing or mouthpiece element 74 in closely assembled relation so as to insure against undesired extrusion of metal, there is provided a swing bolt 92 pivoted as through a pin 93 engaging trunnions 94 on the top of element 74. The bolt 92 is provided with a wing nut 95 which, with the parts in operative relation, coacts with an arm 96 conveniently formed as a projection on the front wall portion 84 of the type tray 80. The arm 96 is provided with a slot 75

100 for the reception of bolt 92, as best shown by Fig. 2.

Although if desired, the mold head assembly 5 may be equipped with mechanical provisions for ejecting the line or slug after casting, it is a present preference, for simplicity of structure, to utilize a separate tool (not shown) for this purpose, and which may conveniently consist of a bar provided with short, right-angled fingers extending from one side thereof, the bar being of a form to be easily introduced between the mold and mouthpiece, and the fingers of the tool being so shaped that with the ejector thus disposed, ejecting pressure may be applied as hereinafter 10 better described, through use of the wing nut 95 and screw 92, with the nut engaging the mold.

The functions and advantage of the casting box attachment, when utilizing the adjustable sliding recessed mold heretofore described, will 20 have been in part apparent from the foregoing description of parts, but it may be noted that, with the type stick disposed in proper relation in the tray 80, and with the mold elevator 22 appropriately adjusted for the predetermined 25 point size of type as through the screw 30 and liner elements 40, all as heretofore described, the mold is latched against the element 74 through engagement of the elements 76 with the pins 77. The type tray 80, with the matrices therein, is 30 then moved upwardly about the hinge 81 so as to bring the tray, mold and element 74 into close parallel adjacency, which position is assured through the casting operation by dropping the screw 92 into notch 100 and tightening the wing nut 95. The plunger 64 is then actuated through rod 65 to displace the requisite quantity of molten type metal upwardly through conduit 62, the throat portion 66 thereof, thence through passages 24 and into the mold cavity. The slug is 40 now cast, and upon freezing, is ready to be removed from the mold, to which end the nut 95 is released, screw 92 removed from slot 100 and swung to an out-of-action position as shown by 45 Fig. 1. The type tray may then be dropped to the position shown by Fig. 1 and but for a subsequent casting of the same line, the type stick is removed from the tray. The mold 10, 11 is then released by opening movement of latches 76, 50 which permits the mold to drop downwardly and forwardly of the backing element 74. At this stage the rear face of the mold is exposed to permit scraping away the feet of the type line with a suitable scraper element or knife (not shown). At this point the ejector tool is 55 inserted between the mouthpiece or backing element, and the mold, with the fingers of the ejector tool engaging the feet areas of the cast slug. With the ejector thus positioned, the swing bolt 60 92 is brought downwardly so that the wing nut may engage the forward face of the mold cap 11. The wing nut is then threaded up, and the pressure thus brought by the ejector against the rear side of the slug will serve to eject the line forwardly from the mold and into the type tray. 65 Following ejection of the slug or line, the ejector is removed, and the tray, mold and mouthpiece assembled as heretofore described, for casting. The foregoing cycle of operation may be now 70 repeated for the same or an additional line as may be desired.

It will have been apparent from the arrangement of rails and grooves 46, 47, 85 and 86 (Figs. 1 and 2) that provision is made for relatively different placements of the matrices in the type 75

tray and hence in different positions relative to the forward face of the mold.

It may be further mentioned as a preference to provide, if desired for centering a short line with respect to the mold, suitable spacer elements 5 abutting the inner face of the fixed end wall 82 of the type tray. It is also desirable to provide, in addition to the usual matrices which may be of conventional type, for casting the several letters of the line, certain blank spacers (not 10 shown) which conform in outline to the letter-forming matrices but which are employed between the different words of the line for purposes of separation, all as is well known in the art.

It will now have appeared from the foregoing description that the mold proper, as well as the attachment and mold appurtenances constructed in accordance with the present invention, serve fully to attain each and all of the objects hereinabove expressed, as well as those implied from the more detailed description.

Although the invention has been described by making particular reference to certain presently preferred embodiments thereof, the description is 25 to be understood in an instructive and not in a limiting sense, since numerous changes may be made in the parts and their assembly, without departing from the spirit and full intended scope of the invention as defined by the claims hereunto appended.

The following subject matter is claimed:

1. In a mold assembly of a type for use with a line casting machine, a mold formed of separable halves, a movable element in one of the mold halves, for setting the mold according to desired point size of type, combined means for adjusting and clamping the movable element in any selected position, a plurality of liners disposable in any selected number in position to serve as 40 a stop for the movable element, and pivot means by which the liners are displaceably attached to one of the halves of the mold.

2. In a mold assembly of a type for use with a line casting machine, a mold formed of separable halves, a movable element in one of the mold halves, for setting the mold according to desired point size of type, combined means for adjusting and clamping the movable element in predetermined position, a plurality of apertured liners 50 movable in any selected number into spacing position relative to the movable element, and pivot means carried by one of the mold halves and extending through the apertures of the liners.

3. In a mold assembly of a type adapted for use with a line casting machine, mold elements defining a casting cavity, one of said elements extending longitudinally of the mold assembly and constituting an elevator adjustable for varying the point size of type to be cast, and a plurality of liners carried by the mold elements, arranged in stacks near the opposite ends of the elevator, and adapted to be moved in selected numbers into and out of functional relation to 60 the elevator.

4. In a mold assembly of a type adapted for use with a line casting machine, mold elements defining a casting cavity, one of said elements extending longitudinally of the mold assembly and constituting an elevator adjustable for varying the point size of type to be cast, a plurality of liners carried by the mold elements, arranged in stacks near the opposite ends of the elevator and adapted to be moved in selected numbers 70 75 75

into and out of functional relation to the elevator, and means for retaining the liners of each stack, in stacked relation, irrespective of their functional relation to the elevator.

5. In a mold assembly for use with a line casting machine, mold elements defining a casting cavity, one of said elements extending longitudinally of the assembly and being adjustable for varying the point size of the type to be cast, 10 a plurality of liners carried by certain of the mold elements, the liners being arranged in superposed groups near the opposite ends of the adjustable element, and adapted to be shifted in selected numbers into and out of functional 15 relation to said adjustable element, means carried by the adjustable element so as to engage the groups of superposed liners and arranged to retain a predetermined number of liners of each group, in out-of-action position with respect to the adjustable element, in accordance 20 with the adjustment of said element.

6. In a mold assembly adapted for use with a line casting machine, a mold including separable cap and base portions, one of said portions including a recess-defining wall adjustable for forming slugs of different point sizes, a plurality of liners pivotally attached to one of said mold portions and arranged to be positioned in selected numbers to constitute stops for said adjustable 25 wall, and means carried by the adjustable wall for retaining predetermined numbers of said liners in out-of-action position, said means serving to indicate, according to position of the adjustable wall, the number of liners insertable in 30 functional relation thereto.

7. In a mold assembly of a type for use in or with a line casting machine, a mold characterized by separable cap and base portions, an elevator adjustably carried by the cap portion, and positionable for forming slugs of different point sizes, a single central adjustment means through actuation of which the elevator may be moved toward and from the base portion of the mold, a group of stacked liners near each opposite end 45 of the elevator, and means for retaining the unused liners in stacked relation, in a number dependent on the adjusted position of the elevator.

8. A mold structure adapted for use in or with a line casting machine, a base member and a cap member detachably assembled to constitute the halves of the mold, a movable wall adjustably carried by the cap, a plurality of liners arranged to be inserted between said movable wall and the base of the mold, the liners being pivotally carried by the base and independently swingable into functional position between the movable wall and the base, each of the liners being apertured between its ends to receive the associated pivot element and so swingably disposed about such element that the liners in use serve to support in stacked relation, those not in use, whereby all of the liners of a given group are retained at all times in stacked relation, irrespective of the functional relation of any selected number of the liners, with the movable wall.

9. In a mold assembly of a type for use with a line casting machine, a cap member, a base member to which the cap is detachably secured, an elevator adjustably carried by the cap member and movable therein in a direction to and from the base to enable an adjustment of the mold cavity for varying the point size of the type to be cast, an adjusting screw normal to

the elevator and pivotally attached at its lower end near the midpoint of the elevator, the screw being in threaded engagement with a portion of the mold cap above the mold cavity, the cap being provided with a recess about the head of said screw to permit access thereto for adjusting purposes from the open front of the mold, a lock nut carried by the screw, and a plurality of liners pivotally carried by the base of the mold and insertable in selected number between the 10 elevator and the base.

10. In a mold assembly of a type for use with a line casting machine, mold elements coacting to define a casting cavity, one of said elements extending longitudinally of the mold assembly 15 and constituting an elevator adjustable for varying the point size of type to be cast, a plurality of liners pivotally carried by one of the mold elements, and arranged in stacks near the opposite ends of the elevator, and a resilient retainer 20 member for each said stack of liners, carried by and in projecting relation from each end of the elevator, the cap, base, elevator, liners and retainer elements being so arranged that the elevator and the liners of each stack are fully visible 25 from the open front of the mold, irrespective of the functional relation of the liners to the elevator.

11. In a type-mold attachment adapted for use in conjunction with a line casting machine, a 30 mold assembly, a reversely curved conduit for molten metal opening at one end into the mold assembly, and serving as a supporting standard therefor, metal displacement means near the other end of the conduit, and adapted for forcing molten metal through the conduit into the mold assembly, and clamping means for detachable securement of the conduit to a metal pot.

12. In a mold assembly for detachable securement to a metal pot of a line casting machine 40 or the like, an apertured mouthpiece or nozzle member, a mold base, a hinge through which the mold base is displaceably secured to the mouthpiece, a mold cap detachably secured to the mold base, a matrix tray and stick-holding structure, 45 a hinge by which the tray is displaceably carried by the mold base, a latch device connecting the mold base and nozzle, and a latch device connecting the nozzle and tray.

13. In a unitary molding attachment for detachable assembly with a metal pot of a line casting machine or the like, an apertured nozzle member, a metal conduit structure terminating in a throat engaging said member, and extending into the metal pot, a mold base, a mold cap detachably secured to the mold base, means for holding an assembled line of matrices in casting relation to the mold parts, hinge means by which the mold base is connected to the nozzle member 55 so as to be capable of movement downwardly and forwardly therefrom, and a pivoted latch connection between the mold base and nozzle member, arranged for releasably retaining the mold and nozzle member in slug-casting relation.

14. In a slug-casting attachment of the general type described and including a mold head, a matrix tray hingedly connected to a forward horizontal margin of the mold head, said tray including a slideable end wall, a closure on the end wall for the unused portion of the forward face of the mold head, and adapted to project endwise beyond the tray and mold head, means for moving the end wall along the tray into its desired position of adjustment, and means for re-

taining the adjustable end wall in predetermined position along the tray.

15. In combination with a slug-casting attachment of the general type described, including a mold head, a tray displaceably carried by the mold head for the reception of matrices, the tray having a fixed end wall and a displaceable end

wall, an actuating arm extending outwardly of the displaceable end wall, and guidingly engaged by the fixed end wall, a clamping screw threadedly engaging the tray and adapted to abut said arm, and means for clamping the tray into line casting relation with the mold head. 5

CLARENCE E. BRANDON, JR.
